UNITED STATES PATENT OFFICE.

CHARLES F. SNOVER, OF BAY CITY, MICHIGAN, ASSIGNOR OF ONE-HALF TO CHAUNCEY GREGORY, OF BAY CITY, MICHIGAN.

STAMP-CANCELING MACHINE.

1,188,109.

Specification of Letters Patent. Patented June 20, 1916.

Application filed July 9, 1914. Serial No. 850,032.

To all whom it may concern:

Be it known that I, CHARLES F. SNOVER,
a citizen of the United States of America,
residing at Bay City, in the county of Bay
5 and State of Michigan, have invented a new,
useful, and Improved Stamp-Canceling Ma-
chine, of which the following, taken in con-
nection with the accompanying drawings, is
a specification fully disclosing the same, such
10 that others may understand the construction
and operation thereof.

This invention relates to stamp canceling machines, and it is the purpose and object of the invention to provide a machine of this character which will cancel large quantities of stamps at one operation, either in sheets containing one hundred stamps or in rolls containing any desired number of said stamps.

20 At the present time stamps are supplied by the Post Office Department to firms which mail out a great deal of second class matter, the stamps being canceled before applying to the mail so that there is no delay
25 after the mail has been received at the post office, as would be necessary if the stamps were not previously canceled. This machine is designed for use by the post office clerks in canceling such large quantities of stamps
30 at one operation, as will be required by such firms.

My invention serving these ends is illustrated in the accompanying drawings, in which:—

35 Figure 1 is an end elevation of the stamp canceling machine; Fig. 2 is a plan view thereof, portions being broken away to better disclose the construction; Fig. 3 is a diagrammatic representation of the assembling 40 of the printing, pressure and inking rolls for the main canceling portion of the machine; Fig. 4 is a side view of a detail used in the construction of the machine; Fig. 5 is a view similar to Fig. 1, but from the opposite end of the machine; Fig. 6 is a view 45 similar to Fig. 3 of the mechanism for canceling stamps in rolls and rewinding the canceled stamps into rolls; and Figs. 7 and 8 illustrate diagrammatically the appearance 50 of rows of stamps after being canceled by the machine.

Like reference characters refer to like parts throughout the several views of the drawing.

55 In the embodiment of the invention, as

shown, two upright frame members 1 are secured in spaced relation to the base 2 and mounted for rotation in said frames, is a cylinder 3, on which cylinder is fastened a rubber stamp or electrotype having the name of the town and State thereon, whereby upon cancelation of stamps the town and State may be printed upon the stamps. Also secured between the frame members in front of the cylinder 3 is a table 4 for receiving the canceled stamps after they have been operated upon by the machine. At one end of the machine a shaft, on which the cylinder is mounted, projects beyond the frame member and, rigidly secured thereto, is a large gear 6 which meshes with a pinion 7 mounted on the stud shaft 8, which in turn has rotative mounting in the frame member 1. A friction wheel 9 of comparatively large diameter is also mounted on said shaft 8 and is secured to the gear 7 whereby rotation being imparted to wheel 9, the gear 7 will be rotated and will correspondingly rotate the cylinder 3.

A friction roller 10 is secured to a shaft 80 which is mounted in the ends of a pair of spaced apart arms 11 pivotally mounted on the frame 1. Adjacent one of the arms 11, an operating handle 12 is pivotally mounted, said handle being provided with a downward extension 13 upon the opposite side of its mounting, to which is attached the coil spring 14 secured to the base 2. Between the arm 11 and handle 12, a second coil spring 15 is located, the influence of such spring tending to draw the arm 11 toward the handle 12 and elevate the roller 10 into engagement with the wheel 9, such movement, however, being limited by a stop formed on the handle 12. The handle 12 extends upwardly and slightly to the rear 95 and carries at its inner side a roller 16 which normally bears against the outer edges of a disk 18 also secured to and rotatable with the shaft on which the cylinder and gear 100 wheel 6 are secured. The said disk 18 is provided at one portion of its periphery with a notch 17 adapted to receive the roller 16. It will be apparent that the roller 16 is normally held against the disk 18 by the 105 action of the spring 14, and that when said roller comes into position opposite the notch 17 it will enter and seat therein. It will also be evident that upon manual operation of the handle to the rear, unseating the roller 110

from said notch, the arms 11 and shaft carried thereby will be elevated, bringing the roller 10 into frictional engagement with the wheel 9, and that upon rotation being imparted to said shaft the cylinder 3 will be correspondingly rotated until the disk has made one complete revolution, bringing the roller 16 again into opposition with the notch 17, upon which the movement of the lever will disengage rollers 9 and 10, and the cylinder 3 will not thereafter rotate until manual operation of the handle is again resorted to. It is, of course, apparent that the handle may be held so that its roller 16 will not seat in the notch 17 and a continuous rotation of this cylinder had, if desired.

Mounted in the frame members 1 above the cylinder 3 is a pressure roller 19, which is grooved at a plurality of places 20 along the length thereof to receive the paper stops 21^a. The roller is held with yielding pressure against the cylinder by means of the springs 21, as shown in Figs. 1 and 5. The paper stops 21^a are secured at their ends to a cross shaft 22 and may be raised and lowered within limits on turning said shaft, as will be evident.

Back of the cylinder 3 and a distance above the front table 4 is a table 23, upon which the sheets of stamps may be placed for feeding into the machine. Below said table, a pair of rollers 24 are mounted in the frame members 1 and such rollers may engage against the cylinder 3 being pressed thereagainst by the coil springs 25, the tension of which is regulated by the screws 26. Said rollers 24 are inking rollers of well known type, and may be used to supply ink to the stamp or electrotype on the outer surface of the cylinder 3. The shaft carrying the roller 10 may be rotated by the pulley 27 attached thereto, said pulley being driven in any suitable manner by any suitable engine or source of power such as an electric motor for instance.

In the operation of the machine so far as described, sheets of stamps may be placed upon the table 23 and fed into the machine, the machine being started by grasping the handle 12 and drawing it to the rear, after which the handle may be released, the roller 10 being held in engagement against the wheel 9 during the rotation of the cylinder until such time as the roller 16 comes into opposition with the notch 17 on the disk 18. The stamps passing between the pressure roller 19 and printing cylinder 3 will have printed thereon the town and State, and it is designed in making the electrotype or stamp for this cylinder that each stamp shall receive at least one imprint of the town and State, as indicated in Fig. 7, and it may be designed that each stamp shall receive such imprint in two places, as shown in Fig. 8, 65 it being evident that with the print, as shown

in Fig. 8, even if the stamps should be fed unevenly through the machine, the State and town would be imprinted upon every stamp passed through the machine. The canceled stamps will fall upon and be received by the table 4, from which they may be removed as needed. At the opposite end of the machine, the shaft on which the cylinder 3 is mounted is projected beyond the frame member and has secured thereon a roller 28, the outer surface of which may be provided with a stamp or electrotype similar to that on the cylinder. Above said roller is positioned a pressure roller 29, which is held by spring pressure thereagainst. The printing roller 28 may be engaged by the inking rollers 30 bearing against the printing roller by yielding pressure, as shown. A spindle 31 is mounted for rotation at a distance from the printing roller 28 and in substantially the same horizontal plane, while on the opposite side a second spindle 32 is rotatively mounted, and is driven by the pulley 33 secured to the shaft to which roller 28 is attached and having driving connection with the pulley 34 secured to and rotatable with the spindle 32. The roller 28 and spindles 31 and 32 are of a width substantially equal to the width of one row of stamps.

In operation, the stamps wound into rolls are placed on the side spindle 31 passing between rolls 28 and 29 and fastened to spindle 32. Upon starting the machine through the manually operating handle 12, roller 28 and spindle 32 will be positively driven, the 95 stamps will be drawn between rollers 28 and 29 and wound upon spindle 32, being canceled in the process, as will be evident. I have shown a member 35 bearing against the row of stamps with light pressure, such member being of utility in preventing unnecessary unwinding of the roll. With this structure a single row of stamps of indefinite length may be canceled and wound into a roll for convenient handling. Stamps are 100 furnished either in flat sheets having a width equal to the width of several stamps or in rolls having a width of one stamp, and this machine is adapted for the cancelation of stamps in either form.

115 Various changes in minor detail may be resorted to without departing from the invention.

The claims define the invention, and I consider myself entitled to all modifications 120 falling properly within their scope.

Having thus described my invention, what I claim as new and desire to secure by Letters Patent, is:—

1. In a stamp canceling machine, a base, 125 spaced apart upright frame members secured to the base, a canceling cylinder mounted for rotation on a shaft carried by and between the frame members, a disk having a notch in its edge secured to the shaft, 130

- a lever pivotally mounted on the outer side of one frame member, a roller on the lever bearing against the edge of the disk, a friction wheel mounted on said frame member, 5 gearing connections between the friction wheel and the shaft, an arm pivotally mounted on the same pivot with the lever, a spring between the arm and lever, a stop limiting the movement of the arm toward the lever, a drive shaft having one end carried at the end of the arm, a friction roller on the shaft adapted to engage with the friction wheel, a downward extension to the lever below its pivot, a spring interposed between said extension and the base normally forcing the roller on the lever against the disk. 10
2. In a stamp canceling machine, a base, spaced apart upright frame members, secured to the base, a canceling cylinder mounted for rotation on a shaft carried by and between the frame members, a disk having a notch in its edge secured to the shaft, a lever pivotally mounted on the outer side 15 of one frame member, a roller on the lever bearing against the edge of the disk, a friction wheel mounted on said frame member, gearing connections between the friction
- wheel and the shaft, an arm pivotally mounted on the same pivot with the lever, a spring between the arm and lever, a stop limiting the movement of the arm toward the lever, a drive shaft having one end carried at the end of the arm, a friction roller on the shaft adapted to engage with the friction wheel, a downward extension to the lever below its pivot, a spring interposed between said extension and the base normally forcing the roller on the lever against the disk, a rearward extension to each frame member, a table positioned above and between and connected to said extensions, spring operated inking rollers movably mounted on and between said extensions back of the cylinder, an upper extension to the frame member, a spring operated pressure roller slidably mounted between said extensions and a table located in front of the cylinder, substantially as described. 20
- In testimony whereof I affix my signature 25 in the presence of two witnesses.
